[57] CLAIM

The ornamental design for a pressed powder compact, substantially as shown and described.

DESCRIPTION

FIG. 1 is a top view of the pressed powder compact embodying our new design;

FIG. 2 is a bottom plan view thereof;

FIG. 3 is a front elevational view thereof;

FIG. 4 is a rear elevational view thereof;

FIG. 5 is a side elevational view thereof;

FIG. 6 is a top view of the pressed powder compact in an open configuration showing a design impressed in the pressed powder in the lower portion of the compact and a mirror in the interior surface of the compact cover; and

FIG. 7 is a side elevational view of the open compact of FIG. 6.
